UNITED STATES PATENT OFFICE.

RICHARD WEBB BURNETT, OF MONTREAL, QUEBEC, CANADA.

RAILWAY-CAR ROOF.

1,152,072.

Specification of Letters Patent. Patented Aug. 31, 1915.

Application filed November 4, 1911. Serial No. 658,611.

To all whom it may concern:

Be it known that I, RICHARD WEBB BURNETT, residing at the city of Montreal, Province of Quebec, Dominion of Canada, have 5 invented certain new and useful Improvements in Railway-Car Roofs, (Case B;) and I do hereby declare that the following is a full, clear, and exact description thereof.

My invention has for its object to provide 10 a comparatively light weight composite wood and sheet-metal roof possessing durability and strength, and consisting of the construction, combination and particular arrangement of parts hereinafter described 15 and pointed out in the claims.

An important advantage of my improved roof is the flexibility thereof and freedom of 20 the roof-sheets to have limited movement relatively to the frame to permit of the play incident to the flexibility of the frame.

For full comprehension, however, of my invention reference must be had to the accompanying drawings forming a part of this specification in which similar reference characters indicate the same parts, and wherein:

Figure 1 is a plan view partly in horizontal section of a roof containing my invention; Fig. 2 is a part longitudinal vertical sectional view and part elevation taken on line A A Fig. 1; Figs. 3 and 4 are transverse vertical sectional views taken on lines B B and C C Fig. 1; and Fig. 5 is a detail transverse sectional view of a portion of the roof and illustrating particularly the manner of 35 connecting the purlins together, the means for supporting the running boards from the carlines without interfering with the freedom of movement of the roof-sheets being also clearly shown.

40 The main supports of my roof are a series of pressed sheet-metal carlines 2 of inverted U-form flanged as at 3 and arched across the car body between the side plates 4. A series of comparatively thin corrugated roof sheets 5 with their side edges 45 bent upwardly as at 6 extend between the carlines and have their ends bent down over the side plates 4. The side edges 6 extend upwardly into the carlines and are suspended therefrom by longitudinal purlin-bars and a series of angular clips 7 each having its upper end offset as at 9 and fastened preferably by electric welding to the interior of the carline and extending beneath and supporting the same out of contact with the car-

line, thus preventing damage to the said roof-sheets by wearing the contiguous portions of the roof-sheets.

It may be observed that the roof-sheets are intact, and consequently, being jointless, are 60 proof against leakage while the edges are effectively protected by the housings provided by the carlines. In order to stiffen and strengthen this roof and brace the car against twisting, and, at the same time, further strengthen the attachment of the roof-sheets to the carlines and afford support for the roof-sheets between the carlines I stretch a series of tension purlin straps or bars 10 65 from end to end of the roof and fasten them at their ends to the end plates 12 of the car body and between their ends to the carlines. The connection with the carlines consists of bolts 13 soldered at their upper ends to the interior of the domes of the carlines and projected downwardly through the purlin bars; nuts 14 serving to clamp these parts together. The straps or clips 7 serve 70 as buffers between the thin roof-sheets and the tension bars, and the bars 10 are preferably of steel pressed to flanged U-form in cross-section. The roof is completed with a 75 wooden member augmenting the metal roof sheets and consisting of a plurality of series of purlins 20, preferably five series, the purlins of each series being alined and fastened in place by sheet-metal straps or saddles 21 resting upon and preferably electrically welded to the carlines and having their ends attached to the ends of the purlins by nails 22 driven therethrough and clenched upon the surface of the flanges of the carlines. Transverse roof boards 25 are nailed to the 80 purlins and their inner ends abut over the middle purlins or ridge-pole and are covered by a running board 26 supported preferably 85 on brackets 27 riveted or otherwise fastened to the carlines. 90

In order to avoid bending the boards to 95 conform to the arched metallic roof-sheets 100 the ridge-pole and side purlins are sufficiently thicker than the intermediate purlins to allow the boards to lie flat.

At the points where the carlines are fastened to the eaves of the car washers 50 are 105 inserted between the turned down ends of the side flanges of the carline and the eaves, and the sheets have eyes 52 large enough to permit of the play incident to the flexibility of 110 the roof. The natural resiliency of the clips

7 cause them to spring open slightly and prevent the roof-sheets being pinched and allow space for flexibility.

What I claim is as follows:—

- 5 1. The combination with a car body of a roof comprising hollow transverse carlines, roof-sheets with upwardly bent edges, angular suspensory straps attached at their upper ends to the interior of the carlines and extending beneath the roof-sheets at a distance below the carline greater than the thickness of the roof-sheets, and means carried by the carline and supporting the said straps separate from and independent of each other.
- 10 2. The combination with a car body of a roof comprising hollow transverse carlines, roof-sheets with upwardly bent edges, resilient angular suspensory straps attached at their upper ends to the interior of the carlines and extending beneath the roof-sheets, at a distance below the carline greater than the thickness of the roof-sheets, and means carried by the carlines and supporting the said straps.
- 15 3. The combination with a car body of a roof comprising hollow transverse carlines, roof-sheets with upwardly bent edges, angular suspensory straps attached at their upper ends to the interior of the carlines and extending beneath the roof-sheets, at a distance below the carline greater than the thickness of the roof-sheets, and purlin bars beneath the straps and supported at their ends by the ends of the car body and bolts welded to the domes of the carlines and projecting downwardly through the purlin bars and having nuts screwed thereon beneath and supporting the said purlin bars.
- 20 4. The combination with a car body of a roof comprising hollow transverse carlines, roof-sheets with upwardly bent edges, resilient angular suspensory straps attached at their upper ends to the interior of the carlines and extending beneath the roof-sheets, at a distance below the carline greater than the thickness of the roof-sheets, and purlin bars beneath the straps and supported at their ends by the ends of the car body and bolts welded to the domes of the carlines and projecting downwardly through the purlin bars and having nuts screwed thereon beneath and supporting the said purlin bars.
- 25 5. The combination with a car body hav-
- ing side plates with holes, and roof frame, certain members of the latter overhanging the car-body and having holes registering with the holes in the side plates, or roof-sheets carried by the roof frame and overhanging the sides of the car body the overhanging portions having elongated holes registering with the holes in the overhanging portions of the roof frame and side plates, distance pieces in the form of washers between the side plates and overhanging portions of the roof frame and within the elongated openings of the overhanging portions of the sheets; and bolts passed through the registering openings and washers and clamping together the side plate washers and overhanging portions of the roof frame for the purpose of securing the roof-sheets to the car body and to the roof frame and providing for the play between the sheets and roof frame incidental to the flexibility of the roof.
- 30 6. The combination with a car body, of a roof comprising hollow transverse carlines, roof sheets with upwardly-bent edges extending within the carlines, and a resilient securing member for said roofing sheets also having a portion extending within said carlines, said securing member having a supporting connection with said carline both above and below the plane of the roofing sheets.
- 35 7. The combination with a car body, of a roof comprising hollow transverse carlines, roof sheets with upwardly-bent edges extending within said carline, resilient angular suspensory straps attached at their upper ends to the interior of the carline, and means for supporting the lower end of said straps from the carline.
- 40 8. The combination with a car body, of a roof comprising hollow transverse carlines, purlins supported from said carlines, roofing sheets positioned between said carlines and purlins, and a resilient buffer interposed between said carlines and purlins, said buffer supporting a roofing sheet.
- 45 In testimony whereof I have signed my name to this specification in the presence of two witnesses:
- RICHARD WEBB BURNETT.
- Witnesses:
- E. R. Pitts,
Gordon G. Cooke.
